BRIDGE CONSTRUCTION

Secondo Ricci, Mishiwaka, Ind.

Application September 22, 1941, Serial No. 411,919

8 Claims. (Cl. 14—17)

This invention relates to bridge constructions. An object of this invention is to provide an improved bridge structure which may be used in either a toy or a full size bridge structure wherein the bridge is constructed of interengaging and interlocking sections.

Another object of this invention is to provide a bridge of the span type which is constructed in interengaging and interlocking sections wherein the intermediate piers or supporting elements are eliminated.

A further object of this invention is to provide a bridge structure of this kind which includes opposed pairs of bridgeheads or abutments from which the span is adapted to extend so that the bridge may be positioned across gulleys, or the like of varying depths.

A further object of this invention is to provide a bridge structure of this kind which, when constructed in the form of a toy may be made out of wood or the like and may be readily put together and taken apart by a child.

A further object of this invention is to provide in a bridge structure of this kind, improved interengaging and interlocking bridge sections which may be constructed in separable units so that the completed bridge may be of any desired length.

A further object of this invention is to provide a bridge structure of this kind which, when completed will be sufficiently strong to withstand the desired load, and which may be formed from either one or both sides of a gully, depression, or the like, the separate units forming the bridge being of such construction that they may be manufactured in fabricated form for quick assembly at the desired location.

A further object of this invention is to provide in a bridge construction of this kind improved key elements which are adapted to be positioned in the center of the span for locking the opposed bridge sections together at the center of the bridge structure.

A further object of this invention is to provide in a bridge structure of this kind a plurality of span forming elements which may be connected together without the use of bolts, rivets, or the like, the bridge construction including upper rails engaging over the lower interengaging units which serve as a reinforcing means for the several units in addition to serving as side rails for the bridge above the floor thereof.

To the foregoing objects and others which may hereinafter appear, the invention consists of the novel construction, combination and arrangement of parts as will be more specifically referred

to and illustrated in the accompanying drawings, but it is to be understood that changes, variations and modifications may be resorted to which fall within the scope of the invention as claimed.

In the drawings:

Figure 1 is a detail top plan of a bridge constructed according to an embodiment of this invention.

Figure 2 is a detail side elevation of the bridge structure.

Figure 3 is a fragmentary longitudinal section of the bridge.

Figure 4 is a fragmentary horizontal section taken longitudinally through one side portion of the bridge, on line 4—4 of Figure 2.

Figure 5 is a sectional view taken on the line 5—5 of Figure 2.

Figure 6 is a perspective view of one of the locking key elements used with this bridge structure.

Figure 6A is a perspective view of the bridge unit disposed at one side of the key shown in Figure 6.

Figure 7 is a fragmentary perspective view looking from the bottom of the inner end portion of one of the rails.

Figure 7A is a fragmentary perspective view of one end of the rail key.

Figure 7B is a fragmentary perspective view looking from the bottom of the outer end of one of the rails.

Figure 8 is a detail top plan partly broken away and in section of a modified form of this bridge structure without the railing structure.

Figure 9 is a sectional view taken on the line 9—9 of Figure 8.

Figure 10 is a fragmentary side elevation partly broken away, and in section, of the central portion of the bridge shown in Figure 8.

Figure 11 is a fragmentary sectional view taken on the line 11—11 of Figure 10.

Figure 12 is a fragmentary perspective view of the key unit associated with the bridge structure shown in Figure 8.

Figure 12A is a fragmentary perspective view of the bridge unit next to the key unit.

Figure 12B is a fragmentary perspective view of one of the interlocking intermediate bridge units, and

Figure 12C is a fragmentary perspective view of one of the intermediate bridge units.

Referring to the drawings, and first to Figs. 1 to 7A inclusive, the numerals 15 and 16 designate a pair of bridgeheads or abutments which are adapted to be positioned at one side of a gully

in spaced apart relation, and may have a portion thereof embedded in the ground for a sufficient distance, so that when the bridge sections are coupled with the bridgeheads 15 and 16, these bridgeheads will not be tilted by the weight of the span sections. The numerals 17 and 18 also designate a second or opposed pair of bridgeheads or abutments which are adapted to be positioned on the opposite side of the gulley, and which are adapted to have portions thereof embedded in the ground for a suitable distance so that the bridgeheads or abutments 17 and 18 will remain vertical during the construction of the bridge.

The bridge, to be more specifically described hereinafter, is formed of a single span extending between the pairs of bridgeheads or abutments and in the present instance, the span is formed of a pair of parallel side span forming members 19 and 20. The two span forming members 19 and 20 are of like construction, and each includes a plurality of span forming units to be herein-after described. The span member 19 is constructed of a pair of outer units 21 and 22 which are adapted to engage in a recess or pocket 23 formed in the two abutments or piers 15 and 17. The units 21 and 22 are of like construction, and each includes upper and lower plates 24 and 25 which are fixed to a vertically disposed web 26.

The plates 24 and 25 are disposed in a substantially horizontal position, and are parallel with each other and the plate 24 constitutes a base plate or flange which has secured to the inner edge thereof a floor supporting flange 27. A plurality of intermediate units 28 are disposed in horizontal alignment with the outer units 21 and 22 and each intermediate unit 28 is constructed of a base flange or plate 29, a top or head flange or plate 30, and a vertically disposed connecting web 31. An inwardly projecting floor supporting flange 32 is formed integral with the inner edge portion of the base flange 28 and is adapted to align with the outer flange 27.

The outer unit 22 is adapted to be connected with the next adjacent intermediate unit 28 by means of a connecting unit 33. The connecting unit 33 is formed of a central solid body 34 and a pair of parallel outwardly extending spaced apart plates or arms 35 which are adapted to engage between the two flanges 24 and 25, and also engage on opposite sides of the web 26. The connecting member 33 is also formed at the opposite or inner end portion thereof with a pair of spaced apart parallel arms or locking members 36 which engage between the lower and upper flanges 29 and 30 respectively, and also engage on opposite sides of the connecting web 31. An inner unit generally designated as 37 is connected to an innermost key or connecting member 38 and is shown more clearly in Figure 6A. There are two of these inner units 37 which are positioned on opposite sides of the transverse median of the span member 19. Each inner unit 37 comprises a base plate or flange 38, and an upper or top flange or plate 39 which is substantially shorter in length than the base plate or flange 38 and which is connected to the lower or base flange 38 by means of a connecting web 40. The base flange 38 is also formed at its inner side with an inwardly extending flange 41 for supporting floor boards or the like. The upper flange or plate 39 has secured to the upper surface thereof a substantially inverted T-shaped block 42.

The stem portion 43 of the block 42 comprises an upwardly extending key, the purpose for which will be hereinafter described. The innermost

connecting member 33 is adapted to engage between the two flanges 38 and 39 on opposite sides of the web 40 as shown in Figure 5.

The span section 19 is formed of a pair of aligned span members generally designated as 19^a and 19^b, each of which is formed of the units and coupling sections hereinbefore described, and adjacent or inner end portions of the span sections 19^a and 19^b are keyed together by means of a centrally disposed key member generally designated as 44. The key member 44 is shown more clearly in Figure 6, and includes a base flange 45, an upper flange 46 and an intermediate body 47. The base flange 45 is formed with an inwardly projecting horizontal flange 48 which is adapted to align with the adjacent floor supporting flange 41 of the innermost units 37.

The key member 44 is formed at each end thereof with an interlocking tongue or web 49 which extends outwardly from the base flange 45 and from the body 47. The tongue 49 is adapted to engage between the adjacent arms of the innermost connecting member 33, the arms of which are substantially longer than the web 40 as shown in Figure 4. The upper flange 44 is substantially longer than the lower flange 45, and the webs or locking members 49 are disposed in substantially dependent relation to the outer portions of the upper flange 46.

The abutments or supporting posts 17 and 18 are formed with an opening 50 extending outwardly from the socket or recess 23, and a beam 51 is adapted to engage in the opening 50, and is formed at its inner end with a pair of spaced apart parallel arms 52 which are adapted to engage on opposite sides of the web 26 of the outer unit 22. The two beams 51 may be used as counterbalancing means, and if desired, similar beams may be associated with the posts or abutments 15 and 16.

The two span elements 19 and 20 are adapted to have connected therewith pairs of rail forming and unit reinforcing members generally designated as 53. The rail forming members 53 comprise a vertically disposed web 54 and a top rail 55. The rail 55 is of T-shape in transverse section which has secured to its outer end as shown in Figure 7B a block or body 56 which is formed with an inwardly extending slot or opening 57. A vertically disposed plate 58 is secured to the abutment 17 at its inner side and the plate 58 has secured thereto or formed integral therewith an inwardly projecting vertical flange 59 which is engageable in the opening or keyway 57. The rail 53 at its inner end as shown in Figure 7 also has secured thereto a block 60 formed with a cutout 62 within which the inverted flanged portion of the T-shaped member 42 is adapted to engage. The block 60 is also formed with a downwardly opening and upwardly extending keyway 61 within which the key or stem member 43 is adapted to engage.

A rail locking key generally designated as 63 is interposed between the abutting inner end portions of a pair of rail forming members 53, and comprises a vertically disposed body 64 which may be formed in an ornamental configuration with a portion thereof extending above the tops of the rails 53. The body 64 at each end thereof is formed with a vertically disposed key or flange 65 which is adapted to engage in the keyway 61 of an adjacent rail block 60. The body 64 is also formed with a shoulder or seat 66 inwardly from the key 65 and coplanar with the upper edge of the key 65, so that the projecting

end portion 67 of the upper flange or plate 55 may rest on the seat 66.

Referring now to Figures 8 to 12C inclusive, the numeral 68 designates generally a span formed of removable span sections which are adapted to be supported between pairs of supporting abutments or posts 69. The span 68 is formed of a pair of span sections 70 and 71 which are of like construction and are disposed in substantial horizontal alignment, the outer end portions of the sections 70 and 71 being seated in openings 72 which are formed in the supporting members 69. The details of construction of the span section 70 are similar in every detail to the section 71, and the span section 70 comprises an outer unit 73 which is formed of a pair of short I-beams 74 which are connected together by a connecting I-beam 75. The connecting I-beam 75 is formed adjacent the outer end portions thereof with cutouts 76 within which the inner portions of the supporting abutments or posts 69 are adapted to engage. The connecting I-beam 75 is substantially smaller in height than the outer I-beams 74, and is welded or otherwise secured at the opposite or outer end portions thereof to the webs 77 of the beams 74.

A plurality of intermediate span forming units 78 similar to units 73 and shown in detail in Figure 12B extend inwardly from the outer span unit 73, and each intermediate unit 78 is formed of a pair of outer I-beam members 79 which are connected together by a connecting or transversely extending I-beam member 80. The I-beam member 80 is connected at the opposite ends thereof as shown more clearly in Figure 12B to the web 81 of each I-beam 79. The connecting or transverse I-beam 80 is of such height as to engage between the upper and lower flanges of the I-beams 79. The adjacent intermediate span unit 78 and the outer units 73 are connected together by locking units generally designated as 82 and shown more clearly in Figure 12C. Each locking unit 82 is constructed of a transversely extending I-beam 83 which has fixed to the outer end portions thereof a longitudinal plate 84. The plate 84 is of a height substantially equal to the distance between the upper and lower flanges of the I-beams 79 and the I-beams 74, and the opposite ends of the plate 84 are adapted to abut against the adjacent transverse I-beams 80 and the outermost I-beams 75.

The I-beams 75 and 80 and the I-beams 83 constitute floor supporting beams upon which floor boards or the like may be mounted, in order to provide a suitable roadway for the bridge structure. At the inner end portion of each unit 70 and 71 there is positioned an inner unit generally designated as 85. The inner unit 85 is constructed of a pair of outer I-beam members 86 which are connected together by a transversely extending I-beam 87. The I-beam 87 is of a height substantially equal to the distance between the upper and lower flanges of the I-beam 86, and preferably the upper flange 88 is substantially shorter in length than the lower flange 89 of the I-beam 86, so that the web 90 will project inwardly from the inner end of the flange 88 and will project upwardly from the flange 89 as shown more clearly in Figure 12A.

The projecting portion of the web 90 forms a key which is adapted to be connected with a central locking unit as will be hereinafter described. The inner or confronting end portions of the span sections 70 and 71 are connected or locked together by a centrally disposed locking

or key unit generally designated as 92. The locking unit 92, which is shown more clearly in Figures 11 and 12, comprises a pair of outer blocks or bodies 93 formed with oppositely extending spaced apart parallel tongues 94 which are adapted to engage on opposite sides of the confronting webs 90 of the innermost units 85. The two blocks 93 are connected together as shown in Figure 12 by means of a transversely extending I-beam 95 formed of upper and lower flanges 95a and 95b respectively which are connected to a web 95c and the lower ends of the pairs of arms or plates 94 are adapted to engage on the lower flanges 89 of the I-beams 86.

15 The bridge structure shown in Figures 8 to 12C inclusive is adapted to have mounted on the outer I-beam members of the several span units aligned pairs of rail forming members 96 which are formed similar in every detail to the rail forming members 53, and which at their inner end portions are formed with a block 97 having a keyway 98 within which the tongues 81 of the inner units 86 are adapted to engage, and within which tongues 99 of a rail key member 100 are 20 adapted to engage. The rail key member 100 is similar in every detail to the rail key member 63 shown in Figure 2.

In the assembly of the bridge structure shown in Figures 1 to 7A inclusive, the abutments or bridgeheads 15 to 18 inclusive are adapted to be firmly secured in the desired location. Where the bridge structure is a full size bridge, the abutments or bridgeheads are adapted to be embedded at the lower ends in the ground on the opposite sides of a gulley, depression, river, or the like. Where the bridge is constructed as a toy, the bridgeheads 15 to 18 inclusive may be secured to a suitable base board or the like. The outermost span forming units 21 and 22 are initially inserted in the openings or sockets 23 of the abutments or bridgeheads and the connecting key members 33 may then be secured to the outermost units 21 and 22. The next or intermediate units 28 may then be connected with the connecting members 33 until the bridge structure is built up to the central portion thereof. The innermost pairs of span forming units 31 are connected with the innermost pairs of connecting members or keys 33, and then the medial key members 44 may be connected with the innermost pairs of span forming units 31.

50 The pairs of rails and reinforcing members 53 may then be placed on top of the side sections 19 and 20, the rail key members 63 being initially placed in position over the key members 44, so that when the rails and reinforcing members 53 are lowered in position these rail members 53 will engage the keys or flanges 65 of the rail key members 63. The outer ends of the bridge may have the beam members 51 positioned in the openings 50 of the abutments, and where the bridge is constructed as a toy, the outer beam members 51 may constitute handles for lifting the completed bridge structure.

65 The bridge structure shown in Figures 8 to 12C inclusive is assembled by initially placing the abutments or bridgeheads 69 in a desired location, and then building the span 68 by initially inserting the outermost span section 73 into the 70 openings 72 of the abutments or bridgeheads, inserting the locking members 82 in the inner end portions of the outer units 73, and then mounting the next intermediate units 78 on the plates 84 of the connecting or locking units 82. The 75 innermost pair of span units are mounted on the

innermost pair of locking or connecting units 82, and then the central key or locking member 92 is inserted in position for engagement with the tongues 90 of the units 85. The rail key 100 may then be placed over the top of the floor unit member 92 and the opposed rails 96 connected with the key members 91 of the innermost pairs of units 85, and also with the key 99 of the central rail key member 100.

Where these two bridge constructions are formed as toys for children, the several sections and units may be constructed out of wood, so as to provide a relatively light weight bridge structure which may be readily handled by a child.

What I claim is:

1. A bridge comprising opposed pair of abutments each formed with an opening in the inner side thereof, outer I-beam sections seated at their outer ends in said openings, intermediate I-beam sections disposed in alignment with said outer I-beam sections, interengaging locking units for said outer and intermediate sections, said locking units engaging between the upper and lower flanges of said outer and intermediate units, an inner pair of I-beam units, and a central key between said inner units, all of said bridge elements being adapted to be interlocked to form a load sustaining bridge without the use of any fastener means such as bolts, rivets or the like.

2. A bridge comprising opposed pair of abutments each formed with an opening in the inner side thereof, outer I-beam sections seated at their outer ends in said openings, intermediate I-beam sections disposed in alignment with said outer I-beam sections, interengaging locking units for said outer and intermediate sections, said locking units engaging between the upper and lower flanges of said outer and intermediate units, an inner pair of I-beam units, and a central key between said inner units, said central key having T-shaped opposite end portions, and the innermost pair of locking units being of such length as to be disposed in a position for engagement with the inner I-beam members and also said central key members, all of said bridge elements being adapted to be interlocked to form a load sustaining bridge without the use of any fastener means such as bolts, rivets or the like.

3. A bridge comprising a pair of span members, each member comprising aligned I-beam members, and locking members for said I-beam members, each locking member comprising an elongated body and a pair of lengthwise extending spaced arms at each end thereof, said arms engaging on opposite sides of the webs of said I-beam members and between the upper and lower flanges of the latter, all of said bridge elements being adapted to be interlocked to form a load sustaining bridge without the use of any fastener means such as bolts, rivets or the like.

4. A bridge comprising a pair of span members, each member comprising aligned I-beam members, and locking members for said I-beam members, each locking member comprising an elongated body and a pair of lengthwise extending spaced arms at each end thereof, said arms engaging on opposite sides of the webs of said I-beam members and between the upper and lower flanges of the latter, each I-beam member including an inner floor supporting flange integral with the lower flange thereof, all of said bridge elements being adapted to be interlocked to form a load sustaining bridge without the use

of any fastener means such as bolts, rivets or the like.

5. A bridge comprising a pair of span members, each member comprising aligned I-beam members, and locking members for said I-beam members, each locking member comprising an elongated body and a pair of lengthwise extending spaced arms at each end thereof, said arms engaging on opposite sides of the webs of said I-beam members and between the upper and lower flanges of the latter, each I-beam member including an inner floor supporting flange integral with the lower flange thereof, a pair of elongated rails and reinforcing members extending lengthwise of said I-beam members and resting on the upper surfaces thereof, upwardly projecting key members carried by certain of said I-beam members, said rails having keyways to receive said key members, and a central locking key member between the inner ends of said rails, all of said bridge elements being adapted to be interlocked to form a load sustaining bridge without the use of any fastener means such as bolts, rivets or the like.

6. A bridge comprising a single span formed of a plurality of span forming units, each unit comprising a pair of spaced apart parallel I-beam members and a transversely extending I-beam fixed to and connecting said pair of I-beam members together, and means for locking said units together, said means including a pair of vertical plates engageable on the inner sides of the webs of adjacent pairs of I-beam members and a transverse connecting beam fixed to said plates between the ends thereof, all of said bridge elements being adapted to be interlocked to form a load sustaining bridge without the use of any fastener means such as bolts, rivets or the like.

7. A bridge comprising a single span formed of a plurality of span forming units, each unit comprising a pair of spaced apart parallel I-beam members, and a transverse beam fixed to said pair of I-beam members between the ends of the latter, a locking unit between adjacent aligned units, each locking unit including a pair of spaced plates positionable between the upper and lower flanges of said I-beam members and against the inner faces of the webs thereof and a transverse beam connecting said plates together, said first and second transverse beams constituting a floor supporting means, all of said bridge elements being adapted to be interlocked to form a load sustaining bridge without the use of any fastener means such as bolts, rivets or the like.

8. A bridge comprising spaced apart pairs of abutments formed with openings in their inner sides, and a single span engaging in said openings and formed of a plurality of span forming units, each unit comprising a pair of spaced apart parallel I-beam members and a transverse beam fixed to said pair of I-beam members between the ends of the latter, a locking unit between adjacent aligned units, each locking unit including a pair of spaced plates positionable between the upper and lower flanges of said I-beam members and against the inner faces of the webs thereof and a transverse beam connecting said plates together, said first and second transverse beams constituting a floor supporting means, all of said bridge elements being adapted to be interlocked to form a load sustaining bridge without the use of any fastener means such as bolts, rivets or the like.
